UNITED STATES PATENT OFFICE

147,343

DESIGN FOR A TOWBOAT

Joseph D. McMichael, Jr., St. Louis, Mo., assignor
to St. Louis Shipbuilding & Steel Co., St. Louis, Mo., a corporation of Missouri

Application November 2, 1945, Serial No. 123,419

Term of patent 14 years

(Cl. D71—1)

To all whom it may concern:

Be it known that I, Joseph D. McMichael, Jr., a citizen of the United States and a resident of the city of St. Louis and State of Missouri, have invented a new, original, and ornamental Design for Towboat, of which the following is a specification, reference being had to the accompanying drawings, forming part thereof.

Fig. 1 is a top plan view of a towboat, showing my new design.

Fig. 2 is a side elevational view thereof, the other side being the same.

Fig. 3 is a forward elevational view thereof,

Fig. 4 is an aft elevational view thereof; and

Fig. 5 is an aft perspective view thereof, looking at the side opposite from that shown in Fig. 2.

The characteristic features of my design are shown by means of full lines in the drawing.

I claim:

The ornamental design for a towboat, as shown and described.

JOSEPH D. McMICHAEL, JR.
